FOLDING CHAIR

John Kovats, Fairfield, Conn., assignor to The Leg-O-Matic Company, Bridgeport, Conn., a corporation of Connecticut

Application April 21, 1931, Serial No. 531,663

2 Claims. (Cl. 155—148)

This invention relates to foldable chairs, and more specifically, to an improved mechanism for folding and extending the chair legs automatically upon moving the back into its folded or extended position; being an improvement of the foldable chair disclosed in my prior application, Serial Number 517,428, filed February 21, 1931.

It is an object of this invention to provide a mechanism for foldable chairs comprising fewer parts and of sturdier construction than those heretofore proposed.

A feature of the present invention is the provision of an improved catch or locking means to maintain the seat in extended position.

Another feature is the provision of a very simple direct one-link connection between the back member and the rear legs for automatically moving the latter into folded and extended position when the back member is moved to these respective positions.

A further feature is the provision of a very simple and very sturdy leg hinge and support construction.

A still further feature is a metal to metal stop means to limit movement of the rear legs into extended position.

And yet another feature of the present invention is the provision of a simple direct connection between the back member and the front legs for automatically moving the legs into folded and extended positions.

Other objects and advantages will be described or apparent as the description proceeds.

In the drawings—

Figure 1 is a perspective view of the improved chair in extended or unfolded position.

Fig. 2 is a perspective view of the chair in folded condition, standing on end.

Fig. 3 is a longitudinal sectional view through the center of the chair, with the parts in extended or unfolded position, and the end portions of the back member and legs being broken away, and with the catch in locking position.

Fig. 4 is a top plan of that portion of the chair shown in Fig. 3, with the seat removed.

Fig. 5 is a longitudinal sectional view through the center of the chair, similar to Fig. 3, but shows the catch released and the legs and back in partially folded position.

Fig. 6 is a sectional view, similar to Figs. 3 and 5, but shows the back and legs in fully folded position.

Fig. 7 is a view similar to Fig. 3, but shows another form of front leg hinge, support and control means.

Fig. 8 is a longitudinal sectional view, similar to Fig. 7, but shows the legs and back in fully folded position.

Fig. 9 is a bottom plan view of a section of the front corner as viewed from the bottom with the leg in extended or unfolded position.

Fig. 10 is an elevation of a section of the front corner of the chair.

As shown in the drawings, the improved chair comprises a seat member 10 preferably including two side bars 11 interconnected with a front bar 12, all of which are recessed as at 13 to accommodate a seat 18 of any suitable material and construction. The seat member may, of course, be square or of any other desired shape, but in its present preferred embodiment it is slightly oblong and flared toward the front so that front legs 14 will be spaced somewhat wider apart than rear legs 15 so as to fold longitudinally adjacent each other on the underside of the seat member in a manner hereinafter more completely described.

In the present construction, each of the front legs 14 is pivoted to the seat member 10 preferably by brackets 16 secured to the underside of the side bar 11 and front bar 12 of the seat member, and having a downwardly extending ear 17 forming a support for a stud 18 upon which the front leg is mounted for pivotal movement into either the folded position shown in Fig. 6, or extended position shown in Fig. 3. A flat portion 19 at the end of each leg engages the bracket 16 to limit movement of the leg into extended position and serves to make the chair more rigid while a cross bar 20 between the two front legs may be used to further brace the chair against sidewise pressure or movement.

The front legs 14 are still further braced in extended position by a toggle 21, preferably one for each leg, comprising a pair of toggle links 22 and 23 pivoted on a stud 24 to the leg and at its other end on a stud 25 to the side bar 11 of the seat member 10, and pivoted intermediate these pivots with a rivet 26. These toggles also serve to fold and extend the legs automatically as hereinafter described.

Secured to the inner side of each of the side bars 11, near the rear ends thereof, is a bracket 27 which is provided with an upper extension 28 and a lower extension 29. The lower extension 29 of each bracket pivotally supports a rear leg 15 and for this purpose the rear legs are preferably provided with plates 30 fixed thereon with bolts 31 and pivotally connected to the lower extension with a stud 32.

The upper extension 28 of each of the brackets 27 is arranged to pivotally support a back member 34 comprising side bars 35 and back panel 36 for movement into either an extended position 5 or a folded position relative to the seat member. Preferably, this is accomplished by securing a plate 37 to each of the bars 35 having a short extension 38 provided with a hole aligned with a hole in the bracket extension 28 with a rivet 10 or stud 39 passing therethrough. The pivot 39 location on the bracket extension 28 and on the plate 37 is offset slightly with respect to the members upon which they are mounted so that the back member 34 may be folded substantially flat 15 against the seat member 10 as shown in Fig. 6.

The structure and pivotal supports of the front leg, back leg, and back member so far described are substantially similar to the construction disclosed in my copending application Serial No. 20 517,428, filed February 21, 1931. Further, it should be understood that although the present Figs. 3 and 6 show the mechanism for the front legs, back legs and back member on one side of the chair, the mechanism is substantially duplicate 25 for the other side of the chair.

Coming now to some of the more important aspects of the present invention, it should be particularly noted that the upper end of each of the rear leg plates 30 is provided with a long forwardly extending offset 40, that each of the back member plates 37 at the lower end is provided with a long forwardly extending offset 41, and a short link 42 is pivotally connected to the offset 40 with a stud 43 and at its other end is pivotally 30 connected to the back member plate offset 41 with a stud 44. This simple link connection of the present invention provides a quick, positive and sturdy means for automatically moving the rear legs 15 into folded or extended position when the back member 34 is moved into either of these positions.

The operation is as follows: In order to move the rear legs 15 from the extended position shown in Fig. 3, into the folded position shown in Fig. 6, 45 the operator need merely grasp the bar 12 of the seat member 34 with one hand and the back member 34 at 45 with his other hand, then swing the back member upon the pivots 39 toward the seat member 10. As the lower end of the back member swings about the pivots 39 it moves the offset 41 down and back while the pivot 44 thereon through the link 42 pulls the pivot 43 on the rear leg plate offset 40 first upwardly then rearwardly to pull the rear leg 15 in a clockwise direction toward the bottom of the seat member about its pivot 32 as shown in the partially folded 50 condition in Fig. 5, and in fully folded position in Fig. 6.

Similarly, according to the present invention, 60 the rear legs are moved into extended position from the folded position automatically by merely swinging the back member away from the seat member 10 on the pivots 39 for, as the offset pivot 44 thereon moves downwardly and forwardly, it 65 pushes the interconnected link 42 and thereby moves the interconnected rear leg offset pivot 43 and rear leg 15 in a counter-clockwise direction on the pivot 32 into the extended position shown in Fig. 3.

Movement of the back member 34 about the 70 pivot 39 into extended position is limited by a side 46 of the lower end of the back member bars 35 engaging the rear edges 47 of the seat member 10. This engagement also serves to support 75 or brace the back member against any heavy

strain or pressure, as when a person leans against it. Interconnected movement of the rear legs into extended position is limited by an edge 48 on the back member plates 37 engaging a cooperating edge 49 on the rear leg plates 30 if desired, and, by the lower ends 50 of the back member bars 35 engaging the top ends 51 of the rear legs 15 at substantially the same time that the side 46 of the back member 34 engages the rear edge 47 of the seat member, as shown in Fig. 3, to provide a rigid support for both the back member and rear legs in the extended position.

These parts are further braced by the rear leg offset 40 pulling on the link 42 and interconnected offset 41 so that the pressure on the rear legs 15 only tends to move the back member 34 more firmly into engagement with the rear edge 47 of the seat member. A cross bar 52 extending between the two rear legs 15 braces the legs against sidewise strain and also makes it possible to use a link 42 connection on only one side of the chair if desired, but for additional strength and to make the chair more positive in its action, it is preferable to provide the link 42 connection on both sides of the chair.

The construction and operation of the rear legs 15 and interconnected back member 34 has just been described in detail without respect to the front legs 14, because in its more specific aspects they may be used with various types of front leg 30 constructions. However, the back member 34 is also arranged to automatically move the front legs 14 into folded and extended positions together with the rear legs 15 when the latter are moved to their respective positions. This is preferably accomplished by providing a long link 53 at two sides of the chair connected at one of its ends to the stud 44 on the back member plates 37 and near its other end by a stud 54 to the front leg toggle 21. Although just one of these 35 links 53 may serve to control both of the front legs 14 when they are provided with the cross bar 20, it is preferable to provide two of these link connections, one on each side of the chair.

With this arrangement then, in order to move all the legs from folded into extended position, it is merely necessary for the operator to grasp the seat member 10 with one hand and move the back member 34 about the pivots 39 in a clockwise direction, as viewed in Fig. 5, and the lower 50 stud 44 in its clockwise movement will push the short links 42 and long links 53 forwardly. The short link 42 swings the rear legs 15 in a counter-clockwise direction on the pivots 32 and the long link 53 extends the front leg toggles 21 so that 55 all four legs may be automatically moved from the closed position shown in Fig. 6 into the open or extended position shown in Fig. 3, by merely moving the back member 34 into extended position—an intermediate position being shown in 60 Fig. 3.

Similarly, all four legs may be quickly folded automatically by merely swinging the back member 34 on its pivots 39 down upon the seat member 10. In this operation the stud 44 will be 65 moved toward the rear of the chair pulling on the short link 42 and long link 53. The long link, because of its pivotal connection 53, breaks the toggles 21 and pulls the front legs 14 in a direction toward the rear and on the underside of the seat member 10 and at the same time the short links 42 pull the rear legs 15 in a direction toward the front and onto the underside of the seat member, preferably between the two folded front legs 14, as shown in Fig. 6.

It should be particularly noted that the present invention provides a novel and very efficient locking means 55 to lock the back member 34, front legs 14, and rear legs 15 in extended position, comprising a catch 56 pivotally mounted on a stud 57 provided with a notch 58 adapted to engage an offset 53 or other similar means on the long link 53. The catch 56 is provided with an angularly disposed section 60 adjacent the 10 seat member front bar 12 and the lower portion of this section is provided with a shoulder 61 adapted to engage the front bar 12 and limit clockwise pivotal movement of the catch plate 56 under the influence of a spring 62.

15 This catch 56 automatically locks the parts in extended position, for, as the back member 34 and interconnected parts are moved toward extended position, the link offset 53 engages a bevel edge 63 of the catch 56 to lift the latter in a counter-clockwise direction, and as the parts reach fully extended position, the notch 58 engages the link off-set 53, as shown in Fig. 3, to firmly lock all the parts in extended position.

Although all four legs and the back member 34 may be locked in extended position with a single catch as shown in Fig. 3, it is at present preferred to extend the section 60 entirely across on the inner side of the front bar 12 to the opposite side bar 11, there to provide it with another 20 right angle bent portion forming a second catch 56 pivoted on a second stud 57 and adapted to engage an offset 59 on the second long link 53. To release the locking means 55, it is merely necessary for the operator to grasp the front of 25 the seat member, then pinch the catch section 60 above the plane of the pivot stud 57 to move the catch in a counter-clockwise direction until the notch 58 moves out of engagement with the long link offset 53. Thereafter the back member 34 30 may be moved about its pivots 39 toward the seat member 10 to automatically move all the legs into folded position, as hereinbefore described.

In the form of chair shown in Figs. 7 to 10 inclusive, the connections between the seat member 10, back member 34 and rear legs 15 are the same as in the form shown in Figs. 1 to 6 inclusive, and hereinbefore described in detail, but with the further provision of a metal to metal stop 70 to limit movement of the rear legs into 40 extended position. These figures also show a particularly advantageous modified form of leg hinge and support, and control mechanism therefor, as will be described in detail hereinafter. Although the various views show the mechanism for only 45 one side of the chair, it should be understood that the various parts are practically duplicated for the other side of the chair.

The stop 70, according to the present invention, preferably comprises an extension 71 on the side plate 27 formed at a right angle to provide a stop shelf 72 and a projection 73 on the rear leg plate 30 adapted to move into engagement with the shelf 72 at predetermined times.

With this metal to metal stop 70, the operator may, in the hereinbefore described manner, grasp the seat member 10 with one hand and the back member 34 with the other hand, then swing the latter about the pivots 39 from the folded position shown in Fig. 8 toward the extended or unfolded position shown in Fig. 7. During this operation, the link 42 through the pivots 44 and 43 on the back member plate offset 41 and rear leg plate offset 40 respectively, pushes the rear legs in a counterclockwise direction about the 50 pivots 32, until the projection 73 engages the

shelf 72, and at the same time the side 46 of the back member bars 35 engage the rear edges 47 of the seat member 10, the edge 48 on the back member plates 37 engages the cooperating edge 49 on the rear leg plates 30, and the lower ends 50 of the back member bars 35 engage the top ends 51 of the rear legs 15.

The particular advantages of the stop 70 are that it provides additional support for the pivotally mounted rear legs 15, especially when a person sits on the chair, and it stops the rear legs, and thereby the back member 34 through the stop edges 48 and 49, in positively the same extended station each time, even though the wood stops 46 to 47 and 50 to 51 shrink considerably, 15 as might occur if the back member 34 and seat member 10 are inadvertently made with green or improperly dried wood.

The modified form of front leg hinge support and control therefor shown in Figs. 7 to 10 inclusive, is particularly advantageous, for it comprises fewer parts than those heretofore proposed, and the parts are substantially concealed. Further, the support is such that it is possible to dispense with the usual unattractive cross bar between the 20 two front legs. In its present preferred form, the hinge support comprises a bracket 75 of triangular shape adapted to extend for a substantial length along the underside of the side bar 11 where it is held by two screws 76 and along the 25 underside of the front bar 12, where it is held by two additional screws 76. This bracket thus serves to greatly strengthen or brace the corner 30 connection between the front bar 12 and side bar 11. The bracket is provided with downturned 35 ears 77 adapted to accommodate a barrelled member 78 portion of a plate 79 on the front leg 14 with a pivot pin 80 extending therebetween, forming the hinge and support 81.

The plate 79 is connected to the rear side of 40 the front leg 14 with studs 82 or any other suitable means, and the barrelled member 78 thereof is offset slightly relative to the top end face 19 of the leg 14 so that the entire top face moves 45 downwardly away from the underside 83 of the bracket 75 when the leg is moved from the position shown in Fig. 7, thereby making it unnecessary to round the corner or cut-away any of the top end 19 of the leg for clearance during pivotal movement in the usual manner. Thus, there is 50 provided a large area of supporting contact between the leg 14 and seat member 10 when the leg is in the extended or load supporting position shown in Fig. 7, which adds greatly to the rigidity 55 of the chair.

The bracket ears 77 are widespaced and the plate 79 is gradually tapered from the bottom toward the top as shown in Fig. 10, and including the barrelled member 78, so that the latter is considerably wider than the chair leg 14; thus, the hinge 81 of the present invention effectively braces the leg 14 against unusual sidewise strain. This feature, and the pivotal connection which makes it possible to provide a large area of contact where the chair leg engages the seat member, provides such a rigid support for the leg that it is unnecessary to provide a usual unattractive supporting or bracing cross bar between the two front legs. Although the type of pivoted leg hinge and support provided by the present invention 60 is especially applicable with the automatic folding chair of the present invention, and with an automatic control to be described hereinafter, it should be understood that it may be used advantageously in non-automatic folding chairs, and 65 70 75 75

may be used to advantage in a folding table or the like.

It should also be noted that the hinge 81 of the present invention provides a very strong pivoted leg construction by making it unnecessary to drill a large trunnion hole through the leg (the usual method), and also, it is not necessary to provide trunnion plates on the sides of the leg with this form of hinge, which make it possible to round the corner 84 between the side bar 11 and front bar 12, to improve the appearance of the chair, and make it possible to provide the chair with round and other unusual shaped legs.

In order to move the front leg 14 on the hinge and support 81 provided by the present invention, together with the rear leg 15, automatically from the folded position shown in Fig. 7 into the extended position shown in Fig. 8, the present invention provides a long link 53' connected at its rear end to the pivot 44 on the back member offset 41 (which connects the short link 42 with the back member offset 41) and extends toward the front of the chair, passing through an aperture 85 provided therefor in the plate 79, to the side of the leg 14 to which it is directly connected by a pivot stud 86.

With this control mechanism, it is merely necessary for the operator to grasp the back member 34 with one hand and the seat member 10 with his other hand, then pull the back member away from the seat member 10 on the pivots 39 to thereby move the pivot 44 on the back member offset 41 downwardly and forwardly and, through the short link 42 and the rear leg offset pivot 43, swings the rear legs about the pivot 32 into the extended position as hereinbefore described. During this movement the pivot 44 also pushes the long link 53' forwardly while the pivot 86 at the front end of the link, through its direct connection with the front leg 14, moves the leg on its pivot 80 until the flat end 19 engages the underside of the bracket 75, as shown in Fig. 7.

The location of the pivots 39 and 44 relative to the pivots 80 and 86 is such that the front leg reaches the extended position at the same time that the rear legs 15 and back member 34 reach their extended position. The front leg 14 is locked in extended position by the long link 53' all the time that the back member is in extended position. In order to automatically move all the legs into the folded position shown in Fig. 8, it is merely necessary for the operator to reverse the operation just described, and pull the back member 34 down onto the face of the seat member 10. One long link 53' extending from the back member 34 to a front leg 14 may serve to move both front legs into extended and folded positions if a cross bar is provided between the two front legs; however, because of the added strength and enhanced general appearance made possible by the omission of a cross bar between the two front legs (which omission is made possible by the sim-

ple and sturdy front leg hinge, support and control of this invention), it is at present preferred to provide a long link 53' at both sides of the chair, one for each of the front legs 14.

The simple and sturdy hinge and support 81 for the front leg 14 and the automatic control having direct connection with the leg, as provided by the present invention, facilitates the operation of automatically moving the legs into folded and extended positions and makes the chair sturdier for use and more positive in its action than chairs of this type heretofore provided. Further, the construction is such that unusual shaped legs may be used, and the working parts are substantially hidden, thereby the general appearance of the chair is also improved.

Variations and modifications may be made within the scope of this invention and portions of the improvements may be used without others.

Having thus described the invention, what is claimed as new and for which it is desired to obtain Letters Patent, is:—

1. A foldable chair comprising a seat member; a back member pivoted to said seat member for movement into either a folded position or an extended position; front legs pivoted to said seat member; a pair of toggle links pivoted respectively to the seat member and front legs and pivoted together intermediate these pivots; rear legs pivoted to said seat member; secondary pivots on said back member and on said rear legs; and actuator links connected to and extending from said back member secondary pivot, one to the pair of toggle links and the other to the secondary pivot on the rear legs to move the front legs and rear legs into folded and extended positions automatically when the back member is moved into folded or extended positions respectively.

2. A foldable chair comprising a seat member; a back member pivoted to said seat member for movement into either a folded or an extended position; front legs pivoted to said seat member; a pair of toggle links pivoted respectively to the seat member and front legs and pivoted together intermediate these pivots and having folded and extended positions; rear legs pivoted to said seat member; secondary pivots on said back member and on said rear legs; a short link connection between said secondary pivots to move the rear legs into either a folded or extended position automatically as the back member is moved to these respective positions; an actuator link connected to and extending from said secondary pivot on the back member to said front leg toggle links to move the latter into either folded or extended position automatically when the back member is moved to these respective positions; and a spring catch on the seat member engaging means on said actuator link to lock the pair of front leg toggle links and the short link connection in the extended positions.

JOHN KOVATS.
